CLAIM

The ornamental design for disposable plastic bag and container therefor, as shown and described.

DESCRIPTION

FIG. 1 is a perspective view of a disposable plastic bag and container therefor, showing our new design;

FIG. 2 is a side elevational view of the bag alone, shown as it appears when closed;

FIG. 3 is an end elevational view of the closed bag;

FIG. 4 is a rear elevational view of the container;

FIG. 5 is a bottom plan view of the container.

The side of the plastic bag container which is not shown is a mirror image of the side which is shown in FIG. 1.
